W. B. S. WHALEY.

TIMING AND INJECTING DEVICE FOR INTERNAL COMBUSTION ENGINES.

APPLICATION FILED OCT. 1, 1917. RENEWED JAN. 3, 1922.

1,426,934.

Patented Aug. 22, 1922.

UNITED STATES PATENT OFFICE.

WILLIAM B. SMITH WHALEY, OF NEW YORK, N. Y., ASSIGNOR TO AMERICAN WHALEY ENGINE COMPANY, OF BOSTON, MASSACHUSETTS, A CORPORATION OF MASSACHUSETTS.

TIMING AND INJECTING DEVICE FOR INTERNAL-COMBUSTION ENGINES.

1,426,934.

Specification of Letters Patent. Patented Aug. 22, 1922.

Original application filed December 21, 1916, Serial No. 138,207. Divided and this application filed October 1, 1917. Serial No. 194,103. Renewed January 3, 1922. Serial No. 526,812.

To all whom it may concern:

Be it known that I, WILLIAM B. SMITH WHALEY, a citizen of the United States, and resident of New York city, in the county of

5 New York and State of New York, have invented a new and useful Timing and Injecting Device for Internal-Combustion Engines, of which the following is a specification.

10 This invention relates to a device for timing and controlling the injection of elastic fluids, as gases, compressed air, or the like, into the combustion chambers of internal combustion engine cylinders for self-starting, reversing, combustion-supporting, stratifying, or scavenging purposes.

This is a divisional application of my co-pending application for improvement in internal combustion engines, filed December 20 21, 1916, Serial No. 138,207, and the invention herein claimed has been further disclosed by me in the two following co-pending applications, to wit, improvement in internal combustion engines, filed January 25 9, 1917, Serial No. 141,401, and improvement in internal combustion engines, filed January 27, 1917, Serial No. 144,970.

The aforesaid co-pending applications disclose and treat with the functions and 30 certain of the uses of the invention herein described, but in order to illustrate the same in this application I have shown in the accompanying drawing an embodiment thereof, wherein:

35 Fig. 1 represents a diagrammatic and partial section of my invention coupled with an internal combustion engine of the type disclosed in my aforesaid co-pending applications.

40 Fig. 2 is an enlarged section taken on line 2—2 Fig. 1, looking in the direction of the arrows, and shows the device diagrammatically coupled with a source of supply therefor.

45 Fig. 3 is an elevational view of the ported sleeve member of the device.

Fig. 4 is a front elevational view of the device.

50 Fig. 5 is a sectional view taken on line 5—5 Fig. 2 looking in the direction of the arrows, showing the automatic injecting valve of the device.

Fig. 6 is a modified view of Fig. 2 showing the use of spacing gaskets and also showing the timing valve as unporting the 55 sleeve-member-ports of the device.

Fig. 7 is a sectional view taken on line 7—7 Fig. 6, looking in the direction of the arrows, showing the auxiliary automatic valve of the device "open" and thus injecting 60 the gas or elastic-fluid into the combustion chamber of the cylinder.

The terms employed herein are used in the generic and descriptive sense, and are therefore not specifically intended as terms 65 of limitation.

Like numerals refer to like parts throughout the several views of the drawing.

The numeral 10 represents the cylinder of an internal combustion engine, preferably of 70 the type disclosed in my aforesaid co-pending applications and which operates on the retarded combustion cycle disclosed in said aforesaid co-pending applications, in which 11 represents the piston shown positioned in 75 head-end-dead-center (Fig. 1) and 12 the clearance chamber of the combustion chamber 13. 16 is the main casing of my device which may be rigidly secured to the cylinder in any suitable manner, as by means of the 80 bolts 17 for example, and is supplied with the bores 18 and 19 which are open to each other by means of the transfer chamber 20. 21 represents the ported sleeve-member of 85 the device and is preferably provided with the gridiron transfer ports 22 (which may be of any desired shape, preferably rectangular), and the retaining flange 23, and is bored to accommodate the reciprocating-valve 24 which has the web 25 thereof preferably 90 perforated with the holes 26 and which has secured thereto or made integral therewith the valve-spindle 27. 28 represents the main valve-bonnet which is preferably provided with the gland retaining 95 means 29 and serves to retain the valve-sleeve 21 in secured position with the device; the retaining flange 23 being supplied with bolt-holes through which the bonnet-bolts 30 will pass for securing both said valve-sleeve 100 21 and said valve-bonnet 28 in working relationship with said casing 16. 31 represents the supply-bonnet which is also secured to said casing 16 and communicates with the

supply-pipe 32 discharging through said supply-bonnet within the valve-sleeve 21 as shown in Figs. 2 and 6.

33 represents the valve-sleeve which fits 5 within the bore 19 of the casing 16 and is provided with the transfer-inlet-port 34, the valve-spindle-supporting-lug 35, and the valve or movable header seat 36; the cylinder end 37 of the valve-sleeve 33 being 10 tightly fitted within the cylinder bore provided therefor as shown. 38 represents the injecting valve or movable header, the spindle 39 of which is slidably supported in the supporting-lug 35 and is supplied with the 15 expansion spring 40 which acts against the retaining collar 41 which is secured to the spindle in any suitable manner. 42 represents the removable valve-bonnet which may be secured to the casing 16 by means of the 20 casing-supporting-studs as shown. 43 represents gaskets, or washers, which may be employed for spacing purposes; that is, for spacing the ported-sleeve in the device to position the ports 22 to yield the required timing for porting the valve operating therein. 25 44 represents cross-head-guides which may be made integral with the main valve-bonnet 28 or may be rigidly secured thereto. 45 represents a cross-head which may be made 30 integral with the main valve-stem 27 or may be rigidly secured thereto and is preferably employed with a device in which the timing valve is actuated through an eccentric as 46 requiring a long eccentric-rod as 47, it being 35 here understood that for short connections the use of the cross-head 45 and the guides 44 may be dispensed with if desired.

Having thus described the parts of my invention in detail, the manner in which the 40 same may be operated is as follows:

First, it will here be noted that the use of the removable type of ported sleeve-member 21 allows for the cutting of the ports 22 accurately in the sleeve, and further enables 45 the ports to be positioned therein to yield the proper timing with reference to the reciprocating action of the valve 24.

Second, it will here be noted that the movable header or injecting-valve 38 normally 50 is held in the "seated" position, as shown in Figs. 1 and 5, by means of the light expansion-spring 40.

Now, with the timing-valve open to a compressed air supply (for example "S") 55 it will be understood from Fig. 2 that as the valve 24 travels downward and the top skirt thereof unports the transfer-ports 22, that the compressed air will flow through said transfer-ports 22, into the transfer-chamber 60 20, through the transfer-inlet-port 34 and into the chamber of the valve-sleeve 33.

With little or no compression in the clearance chamber 12 of the cylinder any compressed air having a pressure in excess of 65 the pressure within the clearance chamber

plus the pressure exerted by the expansion-spring 40 will, after passing through the ports 22 of the device, automatically force the movable header or injecting-valve 38 to become "unseated" and will thus flow into 70 the cylinder. In practice, the device, when used with my "cycle" or "engine" disclosed in my aforesaid co-pending applications, is timed to unport the sleeve-transfer-ports 22 approximately 5° after the engine piston 12 75 passes the head-end-dead-center position in its down or working stroke. Thus it will be observed that with an appreciable pressure of say 114.7 lbs. ab. in the tank S the compressed air will force its way by the header 80 or valve and will cause the piston in the cylinder to start down on its working stroke, thus affecting a so-called "self-starting" feature.

For "completing combustion," the device 85 performs as follows: Assuming this time that an enriched mixture has been properly compressed in the clearance chamber of the cylinder, as per the needs under my aforesaid cycle, to say about 114.7 lbs. ab. 90 (preferably equal to the pressure of the compressed air supply) and the same has been ignited and is burning as the piston is traveling downward, the timing-valve 24 opens the transfer-ports 22 when the piston passes 95 the 5° point beyond the head-end-dead-center, but since the pressure of the burning mixture in the cylinder is now greater than the pressure of the auxiliary injecting compressed air behind the injecting valve, the latter will naturally remain seated and "closed" as shown in Figs. 1 and 5. But, however, as soon as the pressure of the burning mixture in the cylinder drops to a point slightly below that of the pressure 100 of the auxiliary compressed air behind the injecting valve, the latter will automatically "open" as shown in Fig. 7 and will inject the compressed air as long as the main timing-valve will allow the air to flow through 110 it, said timing-valve being timed to "close" the transfer-ports 22 when the piston is nearing its "exhaust" position. This injected compressed air under these circumstances serves to revive the burning action 115 within the cylinder inasmuch as the same supplies the necessary oxygen to complete the combustion of the remaining unburnt fuel constituents within the cylinder, and in that way further work is obtained from the 120 engine and more of the available carboniferous matter in the initial mixture will be utilized and converted into heat units and will thus yield better efficiency than otherwise.

For affecting a so-called "stratifying" feature, the following will be noted, viz:

The main timing-valve is timed, to close the transfer-ports 22 when the piston 11 is nearing its exhaust position, which is prac- 130

- tically at the end of its working stroke. The burning operation in the cylinder (due to the so-called "completing combustion") ceases when the piston reaches approximately two-thirds of its working stroke. Therefore during the interval between the complete combustion point and exhaust the compressed air injected being of a higher pressure than the burnt gases in the cylinder, tends to set up a stratifying condition within the cylinder, resulting in the foul gases (in a vertical type of engine) following the piston while the fresher injected compressed air tends to assume the upper position in the combustion chamber. Thus, when the piston opens the exhaust port the foul gases immediately begin to escape from within the cylinder and are forced out by the expansion of the injected compressed air in the cylinder occurring while the exhaust port is open, leaving the combustion chamber in a clean condition ready to receive the new charge of fuel medium to be ignited and burnt on the next stroke.
- Thus, the device affects the so-called "completing combustion" and then the "subsequent stratifying" operations forming part of my hereinabove referred to improved retarded combustion cycle.
- It will be here noted that if the timing-valve of the device continued to remain open further down on the working stroke of the piston; or would be opened when the exhaust port of the engine opens, that the compressed air injected into the combustion chamber would then serve as a scavenging medium and the device would thus affect a "scavenging operation" within the combustion chamber of the co-related cylinder.
- Thus it will be observed that the device may act in any one or number, or all, of the capacities heretofore explained, but it is more particularly intended, and without being limited thereto, to be used in connection with internal combustion engines operating on my improved retarded combustion cycle as disclosed in my aforesaid co-pending applications.
- It will also be observed that my invention treats with a reciprocating type of piston valve which may be relied upon at all times and which serves as an efficient agent for timing the supply and cut-off of the injecting medium, and is further attended by good wearing qualities. Also, the reciprocating piston valve is provided with perforations which prevent the pocketing of the compressed injecting medium in the valve-casing and also provides for a balancing feature which relieves the device of unnecessary work in the shape of recompressing the medium in the valve-casing, which might otherwise be true if the perforations were not supplied therein, thus requiring the minimum work for actuating the
- same. Also, that the injecting valve 38 serves as a check-valve and will automatically seat itself when the pressure on the outer or cylinder side thereof is greater than that on the valve side, and vice versa the valve 38 will automatically unseat itself when the pressure on the inside or valve side exceeds that on its outer or cylinder side, due to the pressure in the combustion chamber.
- I have described herein one embodiment of my invention, but it is to be understood that the latter is not essentially limited to the specific construction and organization of said embodiment, since the same may be varied without departing from the proper scope of the claims.
- Having thus described my invention, what I claim as new is:
1. In a device of the character described, a casing member having a receiving chamber, a discharging chamber and a transfer chamber communicating between said chambers; a ported sleeve-member fitted within said receiving chamber and porting said receiving chamber with said transfer chamber; a reciprocating valve member slidably fitted in said ported sleeve member and adapted to periodically free the ports of said sleeve member; means for supplying said receiving chamber with elastic-fluid; a protruding discharging sleeve-member fitted within said discharging chamber and adapted to extend through a cylinder wall and open to said transfer chamber and the combustion chamber of said cylinder; and means for normally closing the cylinder end of said discharging sleeve.
  2. In a device of the character described, consisting of a casing member provided with a main receiving compartment and a secondary receiving compartment; an inlet open to said main receiving compartment and communicating with a compressed air supply; a perforated transfer-sleeve-member fitted within said main receiving compartment and adapted to open said main receiving compartment with said secondary receiving compartment; a timing-valve slidably operating in said perforated transfer sleeve member and adapted to time the period of opening between said main receiving compartment and said secondary receiving compartment; an auxiliary and automatic discharge valve positioned within said secondary receiving compartment, normally adapted to keep said compartment closed and otherwise adapted to open to discharge the air therefrom when the timing-valve has uncovered the perforations in the transfer-sleeve-member.
  3. In a device of the character described, a casing having a receiving chamber, a discharging chamber and a transfer chamber communicating between said chambers, said

- 4
- transfer chamber having ports opening respectively into said receiving and discharging chambers and said discharging chamber being adapted to protrude and extend 5 within the walls of an engine cylinder for communicating with the combustion chamber thereof; a reciprocating valve member fitted in said receiving chamber and adapted to operate in connection with the transfer ports thereof; inlet means for supplying said receiving chamber with elastic fluid; and valve means for normally closing the cylinder end of said discharging chamber.
- 10 4. In a device of the character described, a casing having a receiving chamber, a discharging chamber and a transfer chamber

communicating between said chambers, said transfer chamber having gridiron ports opening into said receiving chamber; a reciprocating valve member slidably fitted in said ported receiving chamber; means for supplying said receiving chamber with elastic fluid; a protruding discharging sleeve member fitted within said discharging chamber adapted to extend through a cylinder wall and open to extend through a cylinder 20 wall and open to said transfer chamber and the combustion chamber of said cylinder; and means for normally closing the cylinder 25 end of said discharging sleeve.

WILLIAM B. SMITH WHALEY.
